United States Patent Office

Des. 178,759
Patented Sept. 18, 1956

178,759

HAND LUGGAGE CASE

Abraham S. Braude, Milwaukee, and George H. Wheary,
Jr., Melville G. Farber, and Joe M. Commons, Racine, Wis., assignors to Hartmann Luggage Company, Racine, Wis., a corporation of Delaware

Application September 1, 1955, Serial No. 37,743

Term of patent 14 years

(Cl. D87—5)

FIG. 1.

FIG. 2.

FIG. 3.

Fig. 1 is a perspective view of the top, side, and end of a hand luggage case showing our new design;

Fig. 2 is a side view; and

Fig. 3 is an end view thereof.

We claim:

The ornamental design for a hand luggage case, substantially as shown.
